COMBINATION CLOTHES HANGER

Filed Nov. 27. 1929

INVENTOR,
Allen L. Sackin
BY
Solomon H. Blachef
ATTORNEY

UNITED STATES PATENT OFFICE

ALLEN L. SACKIN, OF NEW YORK, N. Y.

COMBINATION CLOTHES HANGER

Application filed November 27, 1929. Serial No. 410,189.

This invention relates to new and useful improvements in a combination clothes hanger.

The invention has for an object the provision of a device of the class mentioned which is of simple durable construction, dependable in use and efficient in action, and which can be manufactured and sold at a reasonable cost.

10 The invention proposes a coat and trouser supporting section, a shirt and the like clothes supporting section, and a hat supporting section, all sections being in different vertical planes for supporting their clothes in different vertical planes and having a common top bar, and a support hook mounted on said top bar.

For further comprehension of the invention, and of the objects and advantages thereof, reference will be had to the following description and accompanying drawings, and to the appended claims in which the various novel features of the invention are more particularly set forth.

25 In the accompanying drawings forming a material part of this disclosure:

Fig. 1 is a front elevational view of a clothes hanger constructed according to this invention supporting clothes.

30 Fig. 2 is a front elevational view of the clothes hanger, per se.

Fig. 3 is an end elevational view of Fig. 2.

Fig. 4 is a view similar to Fig. 2, but illustrating a modified form of the device.

35 Fig. 5 is another view similar to Fig. 2, but illustrating a further modified form of the device.

Fig. 6 is an edge elevational view of Fig. 5.

40 Fig. 7 is a horizontal sectional view taken on the line 7—7 of Fig. 6.

Fig. 8 is a fragmentary edge view of a clothes hanger constructed according to modified form.

45 Fig. 9 is a fragmentary enlarged vertical sectional view taken on the line 9—9 of Fig. 8.

Fig. 10 is a horizontal fragmentary sectional view taken on the line 10—10 of Fig. 9.

50 The combination clothes hanger consists of a coat and trouser supporting section 10, a shirt and the like clothes supporting section

11, and a hat supporting section 12, all sections being in different vertical planes for supporting their clothes in different vertical planes and having a common top bar 13, and a support hook 14 mounted on the said top bar.

The said coat and trouser supporting section is made from thick sheet metal and consists of a horizontal trouser supporting portion 15 connected with side forming portions 16 and the said top bar 13. The shirt and the like clothes supporting section 11 is made from thick wire and consists of a horizontal bottom portion 17 parallel to the horizontal trousers supporting portion 15 and spaced 60 materially to the front thereof as may be seen from an inspection of Fig. 3, and connected with inclined side forming portions 18 connected with the said top bar 13. A rearward turned hook 19 is arranged upon the center 70 of the horizontal bottom portion 17 and is adapted to receive the shirt or the like clothes.

Said hat supporting section 12 consists of the said common top bar 13, the said inclined side forming portions 18 common to the 75 shirt supporting section 11, vertical side forming portions 20 depending from the ends of the said inclined side forming portions 18 and forward upturned ends 21 providing a space 22 together with the vertical side forming portions 20 for receiving the brim of a hat. A curved wire 23 joins the lower ends of the vertical side forming portions 20.

As shown in Fig. 1, a shirt 24 is shown supported upon the hook 19. Trousers 25 are 80 shown engaged over the trouser supporting portion 15, and a vest 26 and coat 27 is shown engaged upon the side forming portions 16. The brim 28 of a hat 29 is shown engaged in the space provided by the vertical side forming portions 20 and the upturned ends 21. Particular notice is directed that all the various articles are supported in different vertical planes, that is, the trousers depend in one vertical plane, the vest and coat in another vertical plane and surround the trousers, the shirt in a vertical plane materially to the front of the trousers and the hat in another vertical plane to the front of the shirt.

In Fig. 4, a modified form of the device has been illustrated which is very similar to the form just described and corresponding parts may be recognized by similar reference numerals. It distinguishes particularly in the hat supporting section 12^a. This section consists of the said common top bar 13, the said inclined side forming portions 18 common to the shirt and the like clothes supporting section 11, vertical side forming portions 20^a depending from the said inclined side forming portions 18, a horizontal portion 30 connecting the lower ends of the side forming portions 20^a, and a hat clamp 31 supported upon the horizontal portion 30. This hat clamp may be of any conventional construction so as to be adapted to engage the brim of a hat and thus support it.

The modified form illustrated in Figs. 5, 6 and 7, is very similar to the preferred form illustrated in Figs. 1 to 3 inclusive, and similar parts may be recognized by the same reference numerals, but distinguishes in the shirt and the like supporting section 11^b, and in the hat supporting section 12^b. The shirt supporting section consists of a horizontal bottom portion 17 provided with a rearward turned hook 19 and connected with vertical side forming portions 32 connected with the inclined side forming portions 18. The said hat supporting section 12^b consists of a horizontal ring of wire 33 attached upon the lower ends of the vertical portions 32 and firmly held in the horizontal position by supporting struts 34. The crown of the hat may be placed thru the ring 33 and the brim rest upon the ring and thus accomplish supporting. An additional hook 14' is also provided for hanging another hat, cap or the like thereon.

In the modified form illustrated in Figs. 8, 9 and 10, a mounting has been shown for supporting the hook which supports the clothes hanger. This mounting is applicable to all the forms before described. It consists of a transverse horizontal member 35 connected with the said top bar 13 and formed with a top slot 36 extending from the front to the rear. Vertical ends 37 serve to close the ends of the slot. The opposite sides of the slot are formed with inwardly extending flanges 38 forming channels 39. The bases of these channels are formed with serrations 40.

A bottom hook section 41 is connected with a top hook section 42 by a swivel joint 43. The lower end of the bottom hook section is split forming a pair of fingers 43. The resiliency of the metal is depended upon to urge these fingers outwardly. The tips 44 of these fingers are serrated and engage within the channels 39 and normally against the serrations 40. The fingers may be manually pressed together for disengagement from the serrations 40 and then the hook may be moved

to any position along the length of the slot. Upon releasing it automatically engages the serrations and maintains its new position. Such adjustments permit balancing of the hanger according to the clothes engaged thereon. For example, if merely a hat is engaged on the hanger, the hook must be moved to a different position in order to balance the hanger in the vertical. Likewise if a coat, vest and shirt are supported upon the hanger, the hook must be correspondingly moved.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A combination clothes hanger, comprising a coat and trouser supporting section, a shirt and the like clothes supporting section, and a hat supporting section, all of these sections being in different vertical planes for supporting their clothes in different vertical planes and having a common top bar, and a support hook mounted on said top bar, said hat supporting section consisting of the said common top bar, inclined side forming portions connected with the top bar, vertical side forming portions connected with the bottom ends of the inclined side forming portions and formed with upward turned ends providing a space with the said vertical side forming portions for receiving the brim of a hat.

2. A combination clothes hanger, comprising a coat and trouser supporting section, a shirt and the like clothes supporting section, and a hat supporting section, all of these sections being in different vertical planes for supporting their clothes in different vertical planes and having a common top bar, and a support hook mounted on said top bar, said hat supporting section consisting of a horizontal ring of wire attached to vertical side forming portions connected with inclined side forming portions in turn connected with the said top bar.

3. A combination clothes hanger, comprising a coat and trouser supporting section, a shirt and the like clothes supporting section, and a hat supporting section, all of these sections being in different vertical planes for supporting their clothes in different vertical planes and having a common top bar, a support hook mounted on said top bar, and means for adjustably supporting said support hook for balancing the clothes hanger to maintain vertical position according to the clothes engaged thereon.

4. A combination clothes hanger, comprising

ing a coat and trouser supporting section, a shirt and the like clothes supporting section, and a hat supporting section, all of these sections being in different vertical planes for
5 supporting their clothes in different vertical planes and having a common top bar, a support hook mounted on said top bar, and means for adjustably supporting said support hook for balancing the clothes hanger
10 to maintain vertical position according to the clothes engaged thereon, comprising a transverse horizontal member connected with the said top bar and formed with a slot extending from the front to the rear
15 end and formed with inwardly extending flanges across the top portion of the slot for forming channels, serrations in the bases of said channels, and a hook with a bottom split end forming fingers normally urged
20 apart and engaging in the said channels and against said serrations for maintaining adjusted positions.

In testimony whereof I have affixed my
signature.
